UNITED STATES PATENT OFFICE.

WILLIAM S. SCHROEDER, OF AUSTIN, ILLINOIS, ASSIGNOR TO CHARLES A. SCHROYER,
OF OAK PARK, ILLINOIS.

YOKE FOR DRAFT-GEAR.

1,256,266.

Specification of Letters Patent. Patented Feb. 12, 1918.

Application filed July 14, 1915. Serial No. 39,734.

To all whom it may concern:

Be it known that I, WILLIAM S. SCHROEDER, a citizen of the United States, residing in Austin, in the county of Cook and State 5 of Illinois, have invented a new and useful Improvement in Yokes for Draft-Gears, of which the following is a specification.

This invention relates in general to yokes for draft-gears and has for its object 10 broadly the provision of a yoke for a draw-bar from which the draw-bar and the follower plates and attendant parts can be separately removed without removing the yoke from the draft-rigging and without 15 the use of sacks or other auxiliary supports.

A further object of the invention is the provision of a structure of this character in which the draw-bar may be positioned by inserting the butt into the yoke from the 20 front, thereby permitting positioning of the draw-bar after the installation of the yoke in the draft-gear is complete.

A still further object of the invention is the provision of such a structure in which 25 the draw-bar when secured will engage on all four sides.

Other objects and advantages of the invention will be apparent as it is better understood from the following description when 30 considered in connection with the accompanying drawing illustrating a preferred embodiment thereof.

Referring to the drawings,

Figure 1 is a perspective view of a yoke 35 embodying my invention;

Fig. 2 is a horizontal section taken through the same and showing a draw-bar in position;

Fig. 3 is a vertical section of the same;

Fig. 4 is a section taken substantially on the line 4-4 of Fig. 3;

Fig. 5 is a partial perspective view of the head of the yoke embodying my invention;

Fig. 6 is a partial perspective of the 45 hooked end of the movable limb of the yoke; and

Fig. 7 is a partial perspective view of the part of the stationary limb with which the hooked end of the movable limb engages.

For the purpose of illustrating my invention I have shown on the drawing a yoke generally designated at A in which is secured the butt B of a draw-bar C and in which is carried follower plates E held apart 50 by the usual spring F.

The yoke embodying my invention is comprised of two parts or limbs 11 and 12, the limb 11 being stationary when the yoke is secured in a draft-gear and the limb 12 having movement with respect to the limb 11 in 60 a plurality of directions, as will be later described. The limb 11 carries a tail 13 and a head 14, the tail 13 serving to connect the limb 12 with the limb 11 and the head 14 to retain it in the spaced relation required to 65 provide the channel or space for the follower plates. The head 14, which is formed on the forward end of the limb 11, is adapted to receive the butt B of the draw-bar from the front. The draw-bar and its butt 70 are of ordinary standard construction, the butt being larger than the shank 15 which connects it with the coupler head 16. This arrangement provides a pair of oppositely disposed shoulders 17 and 18 at the top and 75 bottom of the butt.

Between the shoulders 17 and 18 an aperture 19 is provided for the reception of a key 21. In accordance with my invention it is intended that the butt with the key in 80 place shall be inserted through the forward face or wall of the head 14 of the yoke and after insertion be lifted to bring the draw-bar to its final operative position. When the draw-bar is inserted in the yoke the ends 85 22 of the key 21, which extend beyond the vertical faces of the butt and constitute projections thereupon, enter into the open ends 23 of guide-ways 24, one such guide-way being provided in the inner face of each side 90 vertical wall of the yoke head. These guide-ways are offset, as will be seen from Fig. 1, so that after the butt enters the yoke head it may be lifted to dispose the ends of the keys in the offset portions 25 of the guide-ways. These offset portions provide shoulders 26 at the front for engagement with the ends 22 of the key when the draft-gear is in 95 service. The upper or stationary limb 11 is provided at its front with a downwardly 100 extending shoulder 27 behind which the upper shoulder 17 of the butt of the draw-bar engages. The lower shoulder 18 engages behind a shoulder 28 formed for the purpose at the forward end of the limb 12. This 105 shoulder lifts the draw-bar from its position immediately after insertion into the yoke head into final operative position through a movement across the yoke. The limb 12 carries at its rear end a hook 29 110

having rounded under surfaces 31 which engage over the top of a wall 32 the side of which is concave, as seen at 33, to give a double pivotal movement to the limb 12, 5 one of such pivotal movements permitting swinging of the limb across the yoke, and the other permitting it to drop down vertically under certain conditions. When the butt of the draw-bar is inserted the limb 10 12 is disposed in the position shown in full lines in Fig. 1. That is, to say, it is swung transversely with respect to the yoke to dispose the shoulder 28 to one side to permit entrance of the draw-bar butt. The shoulder 15 28 extends upwardly from the limb 12 and a second shoulder 35 extends downwardly. The lower face of this shoulder is beveled at 36 and rides upon a beveled surface 37 provided on the floor or upper face 20 of the bottom wall 38 of the yoke head. When one beveled face slides over the other the draw-bar will be lifted and engagement formed between the draw-bar and the yoke at all four walls of the yoke head, the two 25 vertical walls with ends of the key and the two horizontal walls with the shoulders 17 and 18 of the draw-bar butt. Movement of the arm 12 across the yoke is limited by a bolt or other suitable means 39 which extends 30 through a lug 41 and through an elongated slot 42 in the shoulder 35. At the outer end the shoulder 35 is provided with a downwardly extending lug 43 adapted to contact with the edge of the bottom wall 38 of the yoke head and at the opposite side a perforated lug 44 is provided which passes through an aperture 45 in the opposite vertical side wall of the yoke head to permit engagement with a cotter pin 46 to hold the 40 parts against any relative movement.

It will be manifest from the foregoing that the draw-bar may be readily removed and positioned without removing the yoke from the draft-gear merely by taking out 45 the cotter pin 46 and shifting the limb 12 to the side, as shown in full lines in Fig. 1. When, however, it is desired to remove the follower plates and the spring and other attendant parts, the cotter pin 46 and bolt 50 39 are removed and the movable end of the limb 12 swung out until it is free of the head, when it may be lowered through its vertical pivotal movement, *i. e.*, dropped down out of the way.

From the foregoing it will be seen that the movable end of the limb 12 has two 55 separate movements, one to the side to permit removal of the draw-bar and the other downwardly from said side movement to 60 permit removal of the follower plates and associated parts and mechanism. When properly constructed, the movement of the limb 12 to take out the follower plates will not cause removal of the draw-bar, the 65 draw-bar merely dropping down somewhat as the shoulder 28 is removed, but not sufficiently to permit it to fall out of the yoke. The ends 22 of the key are inclosed wholly within the head of the yoke, although they need not be, and if desired the key may be 70 made integral with the draw-bar. In the present instance the rear part of the key is cut away at 51 to give the draw-bar the desired travel in buffing.

It is thought that the invention and many 75 of its attendant advantages will be understood from the foregoing description, and it will be apparent that various changes may be made in the form, construction and arrangement of the parts without departing 80 from the spirit and scope of the invention or sacrificing any of its material advantages, the form hereinbefore described being merely a preferred embodiment thereof.

I claim:

1. A yoke for a draft-gear provided with a pair of shoulders for engagement behind the butt of a draw-bar, one of said shoulders being shiftable across the draw-bar in parallelism with the other to permit insertion 90 and removal of said draw-bar, and means for limiting the shifting movement of said shoulder.

2. A yoke for a draft-gear comprising a pair of connected limbs having a plurality 95 of relative movements while connected, one of said movements permitting removal of the draw-bar while the yoke is in position in the draft-gear, and a subsequent relative movement permitting removal of the follower plates and attendant parts while said yoke is in position in the draft-gear.

3. A yoke for a draft-gear comprising a pair of connected limbs, one of said limbs being movable with respect to the other in 105 both horizontal and vertical planes, movement in one plane serving to permit removal of a connected draw-bar and subsequent movement in the other plane permitting removal of the follower plates and attendant parts.

4. A yoke for a draft-gear comprising a pair of connected limbs, one of said limbs being movable relatively with respect to the other successively while connected in a plurality of directions, movement in one direction permitting release of a connected draw-bar and movement in the subsequent direction permitting removal of the follower plates and attendant parts.

5. A yoke for a draft-gear comprising a pair of limbs pivotally connected to swing relatively in a plurality of planes.

6. A yoke for a draft-gear comprising a pair of limbs connected by a single pivot 125 permitting relative swing of one limb with respect to the other in a plurality of planes.

7. A yoke for a draft-gear having a head at its front and provided with offset guide-ways on opposite inner faces, and a draw-

bar having a butt provided with projections movable in said guide-ways, said yoke having means for restraining movement of said projections to predetermined parts of said guide-ways when the parts are operatively connected.

8. A yoke for a draft-gear comprising a head into which the butt of a draw-bar may be inserted from the front, shoulders within said head for engaging four sides of said draw-bar butt, and means for holding the butt of said draw-bar into engagement with said shoulders.

9. A yoke for a draft-gear comprising a head into which the butt of a draw-bar may be inserted from the front, shoulders within said head for engaging four sides of said draw-bar butt, and a single member for retaining all of said shoulders in operative relation with the butt of said draw-bar.

10. A yoke for a draft-gear comprising a head in which the butt of a draw-bar may be inserted, a draw-bar provided with a key extending therethrough and projecting on opposite sides thereof, and guide-ways within the head of said yoke for receiving the ends of said key, said guide-ways being offset to provide shoulders for engagement by the key.

11. A yoke for a draft-gear comprising a head into which the butt of the draw-bar may be inserted when the draft-gear is in operative position, shoulders within said head for engaging four sides of the butt of said draw-bar and means for holding said butt in said four sided engagement with said shoulders.

12. A yoke for a draft-gear comprising a head having offset guide-ways on opposite inner faces and having shoulders on its four sides, opposite shoulders being insertible into said guide-ways, shoulders within the head for engaging the shoulders on the four sides of said draw-bar and a single member for retaining all said shoulders in operative relation.

13. A yoke for a draft-gear comprising a head having offset guide-ways in its opposite inner vertical faces and having upper and lower shoulders adapted to engage in front of the butt of a draw-bar, a lateral key through the draw-bar and insertible in said guide-ways, and a single member for holding said shoulders for engagement with the front of the butt of said draw-bar and

the ends of said key in locked engagement with the yoke while in said guide-ways.

14. A yoke for a draft-gear comprising a head in which the butt of a draw-bar may be inserted and a draw-bar provided with a key extending laterally therethrough and projecting on opposite sides thereof, the head of said yoke having offset shoulder guide-ways for receiving the ends of said key and a lateral sliding member supported on the floor of the yoke for retaining said key in said offset guide-ways.

15. A yoke for a draft-gear comprising a head having a horizontal extending shoulder at its top and adapted to engage behind the butt of a draw-bar and having transverse openings near its bottom and a sliding member having a shoulder adapted to be disposed beneath the first mentioned shoulder and having a part adapted to be disposed beneath the butt of the draw-bar, said member being of wedge shape to lift the draw-bar into engagement with the shoulder at the top of the yoke.

16. A yoke for a draft-gear, comprising a head having offset guideways in its inner side walls and adapted to receive a butt having lateral projections, said projections being movable in said guideways in service, and the forward limiting walls of the offset parts of said guideways serving as shoulders for engagement of said projections.

17. A yoke for a draft-gear, comprising a head having upwardly offset guide-ways in its inner side walls, and adapted to receive a butt having lateral projections and a supporting sliding locking member movable transversely of the head for holding said butt in elevated position with said projections behind the offsets in said guide-ways.

18. A yoke for a draft gear comprising a head having upwardly offset guide-ways in its inner side walls, and adapted to receive a butt having lateral projections and a supporting sliding locking key movable transversely of the head for holding said butt in elevated position with said projections behind the offsets in said guide-ways.

In testimony whereof, I have hereunto set my hand in the presence of two subscribing witnesses.

WILLIAM S. SCHROEDER.
